UNITED STATES PATENT OFFICE.

CHARLES F. SCHRINER, OF CLEVELAND, OHIO, ASSIGNOR TO THE NATIONAL STEEL BARREL COMPANY, A CORPORATION OF OHIO.

MEASURING PUMP.

Application filed April 17, 1922. Serial No. 553,851.

To all whom it may concern:

Be it known that I, CHARLES F. SCHRINER, a citizen of the United States, residing at Cleveland, in the county of Cuyahoga and 5 State of Ohio, have invented certain new and useful Improvements in Measuring Pumps, of which the following is a specification.

This invention relates to measuring 10 pumps for grease, oil or other liquids, and more particularly to the means for limiting the movement of the piston thereby measuring a quantity pumped.

The main object of the invention is to 15 provide a measuring pump of said character, which may be set to pump a smaller quantity as a pint, and then set to pump a larger quantity as a quart without the necessity of returning the pump piston to its 20 original position after the pumping of the first quantity.

Another object of the invention is to provide a measuring pump of said character having means for adjustment in order that 25 correct smaller and larger quantities may be pumped.

With the above and other objects in view as will be readily understood, the invention will be hereinafter fully described as 30 illustrated in the accompanying drawings, and the novel features thereof will be particularly pointed out in the appended claims.

In the drawings similar characters of reference are used in the several views of 35 the drawings to indicate corresponding parts.

Figure 1 is a side elevation of a pump with a measuring device constructed in accordance with my invention applied there- 40 to,

Fig. 2 is a cross-sectional view, taken on line 2—2 of Fig. 1,

Fig. 3 is a vertical sectional view illustrating the measuring device when the push 45 pin is set in its lower position,

Fig. 4 is a similar view after the push pin of the measuring device has been forced to its higher position,

Fig. 5 illustrates a front view of the 50 upper part of Fig. 3,

Fig. 6 is a cross-sectional view, on an enlarged scale, taken on line 6—6 of Fig. 3, illustrating the hand lever of the push pin in its first set position, and

Fig. 7 is a similar view, the hand lever

being arranged in alignment with the vertical slot of the tube.

Referring to the drawings, 1 represents the body or barrel of a grease pump having at its lower end an inlet pipe 2 for fitting 60 into a barrel from which the contents are to be pumped, and at its upper end a discharge nozzle 3. A suitable piston 4 is slidably mounted in the body 1, and fixed thereto is an upright rod 5 having teeth 65 adapted to be engaged by a pinion 6 of a shaft 7, which is rotated by means of a crank-handle 8 for reciprocating said piston. The piston rod 5 extends through a central opening 9 in the upper end or head 70 of the body 1. Fixed to said upper end of the body is an upright tubular member 11, which is adapted to receive the piston rod 5 as it is forced upwardly, and to the upper end of said tubular member is fixed 75 a reducer 12.

A push pin 13 is slidably mounted in said reducer, and a vertical tube 14 is fixed thereto for receiving said push pin as it is moved upwardly. Forming a part of and extending from the top 80

of the push pin 13 is a hand lever 15, which is adapted to be moved in and out of a horizontal slot 16 in the reducer 12, either to set the push pin at its lower position, or turn the hand lever so that it will be in 85 alignment with a vertical slot 17 in the reducer and a slot 18 in the tube 14 aligning therewith to allow said push pin to move upwardly to its higher position.

A lug 19 is formed integrally with the reducer 12 above the horizontal slot 16, and threaded therein is a screw 20 which is adapted to be engaged by said hand lever for serving as an adjustable stop for the push pin, and a similar screw 21 is threaded in the closed 90 upper end of the tube 14 for engaging the upper end of the push pin to limit its higher movement.

In practice, the piston rod 5 and the push pin 13 are of such length that, when the piston 100 4 in its upper movement has discharged a certain quantity from the pump, as a pint, the upper end of the piston rod will engage the lower end of the push pin and thus limit the movement of the piston due 105 to the hand lever 15 being set in the horizontal recess 16 and engaging the stop screw 20. If it is desired to pump a larger quantity, as a quart, without reversing the crank-handle 8, the hand lever 15 is set in 110

alignment with the vertical slot 17 of the reducer and the slot 18 of the tube 14. The piston 4 may then move upwardly and lift the push pin 13 until its upper end engages 5 the stop screw 21, thereby discharging a quart. Upon reversing the crank-handle 8, the piston will fall and allow the push pin 13 to return to its original position.

From the foregoing, it is obvious that a 10 smaller or larger quantity of grease or the like may be discharged from the pump without reversing the crank-handle for operating the same, that the device for accomplishing said purpose is readily set, and 15 that adjustments are provided for accurate measurement. Although the device illustrated in connection with a pump is well adapted to accomplish the intended purpose, it will be understood that slight 20 changes in the details of construction may be made within the scope of the claims.

Having fully described my invention, what I claim is:

1. In a measuring pump, the combination 25 of a body, a piston in the body, a rod having its lower end fixed to the piston, means for actuating the piston, a tubular member adapted to receive the upper end of the rod, a push pin slidably mounted in the tubular member adapted to be engaged by the upper 30 end of said rod, and means for holding the push pin in a set position, substantially as described.

2. In a measuring pump, the combination 35 of a body, a piston in the body, a rod having its lower end fixed to the piston, means for actuating the piston, a tubular member adapted to receive the upper end of the rod, a push pin slidably mounted in the tubular member adapted to be engaged by the upper 40 end of said rod, the tubular member having a vertical slot, a hand lever fixed to the push pin and adapted to slide in said vertical slot, and the tubular member being provided with a horizontal recess for receiving 45 the hand lever, said recess being of sufficient height to permit vertical movement of the hand lever therein, adjustable means for limiting the vertical movement of the hand lever in said recess, and adjustable means 50 adapted to be engaged by the upper end of said push pin for limiting the upward movement thereof, substantially as described.

3. In a measuring pump, the combination 55 of a body, a piston in the body, a rod having its lower end fixed to the piston, means for actuating the piston, a tubular member adapted to receive the upper end of the rod, a push pin slidably mounted in the tubular member adapted to be engaged by the upper 60 end of said rod, the tubular member having a vertical slot, a hand lever fixed to the push pin and adapted to slide in said vertical slot, the tubular member being provided with a horizontal recess for receiving 65

the hand lever, said recess being of sufficient height to permit vertical movement of the hand lever therein, and adjustable means for limiting the vertical movement of the hand lever in said recess, substantially as 70 described.

4. In a measuring pump, the combination of a body, a piston in the body, a rod having its lower end fixed to the piston, means for actuating the piston, a tubular member 75 adapted to receive the upper end of the rod, a push pin slidably mounted in the tubular member adapted to be engaged by the upper end of said rod, and adjustable means adapted to be engaged by the upper 80 end of said push pin for limiting the upward movement thereof, substantially as described.

5. In a measuring pump, the combination of a body, a piston in the body, a rod having its lower end fixed to the piston, means for actuating the piston, a tubular member adapted to receive the upper end of the rod, a push pin slidably mounted in the tubular member adapted to be engaged by the upper 85 end of said rod, the tubular member having a vertical slot, a hand lever fixed to the push pin and adapted to slide in said vertical slot, the tubular member being provided with a horizontal recess for receiving 90 the hand lever, said recess being of sufficient height to permit vertical movement of the hand lever therein, adjustable means for limiting the vertical movement of the hand lever in said recess, and adjustable means 95 adapted to be engaged by the upper end of said push pin for limiting the upward movement thereof, substantially as described.

6. In a measuring pump, the combination 100 of a body having a vertical bore, a piston in the body, a rod having its lower end fixed to the piston, means for actuating the piston, a tubular member extending from the body in alignment with and adapted to receive the upper end of said rod, a reducer fixed to the upper end of said tubular member, a tube fixed to the upper end of said reducer, a push pin loosely mounted in the reducer and adapted to be engaged by the upper end of said rod, the push pin 110 being provided with a horizontal hand lever, the reducer being provided with a horizontal slot adapted to receive the hand lever, and said tube being slotted for receiving said hand lever when the hand lever is set 115 in alignment therewith, substantially as described.

In testimony whereof I affix my signature.

CHARLES F. SCHRINER.
